EXHAUST HOOD

Jack Hyde, Pittsburgh, Pa., assignor to Koppers Company, Inc., a corporation of Delaware
Filed July 15, 1965. Ser. No. 472,229
11 Claims. (Cl. 122—7)

ABSTRACT OF THE DISCLOSURE

An exhaust metallurgical hood comprises a reticular frame of fluidly intercommunicative tubular members through which cooling water flows, and refractory panels that fit the reticular frame and form the walls of the hood. The panels are removably secured to the frame and may individually be removed and reinstalled when it is desirable to do so.

This invention relates to metallurgical furnaces and, more particularly, to an exhaust receiving apparatus or hood for receiving and conducting the hot effluent discharge from a basic oxygen furnace, and the like.

When oxygen is introduced into a basic oxygen furnace during the steel refining process, great quantities of effluent, such as gases, fumes, and dust, are produced by the reaction of the oxygen and the hot metal temperature of the effluent discharge may reach 3500° F., or an even higher temperature. During the blowing time, which may last from 20—22 minutes or longer, the rate of discharge of the gases may be in the order of 175,000 cubic feet per minute or more.

An exhaust receiving hood is customarily used to receive and conduct the hot effluent gases from the furnace region to other apparatus which cleans and treats the gases. Because the gas temperature is so high, it is necessary to cool the hood structure lest it melt under operating conditions. Heretofore furnace hoods have been provided with water jacket type shells or envelopes in which water or other cooling fluid flowed and which cooled the hood envelope. Such hoods, however, are heavy and there was always a very present danger of a leak which would cause water to enter the furnace.

Other types of hoods have utilized a plurality of adjacent fluid-carrying tubes arranged in much the same fashion as the tubes comprising the steam generator water-wall in a boiler. In such instances, however, the weight of the hood is excessive and that there is no simple way to make effective repairs whenever a leak occurs, has been a serious problem. For these and other reasons, the hoods heretofore available have not been entirely satisfactory.

In the present invention, a metallurgical furnace hood comprises: a reticular frame comprised of spaced apart members; a plurality of panels each comprised of a grid structure and refractory material secured to the grid; and means to removably secure the panels to the reticular frame thereby forming the effluent guiding walls of the hood.

For a further understanding of the present invention and for advantages and features thereof, reference may be made to the following description taken in conjunction with the accompanying drawings which show for the purpose of exemplification, embodiments of the invention.

In the drawings:

FIG. 1 is a schematic side elevational view of one embodiment of an exhaust hood of the present invention;

FIG. 2 is a front elevational view along line II—II of FIG. 1;

FIG. 3 is a perspective view along line III—III of FIG. 1;

2

FIG. 3a is a schematic view of a typical panel securing member;

FIG. 4 is a schematic perspective view of a portion of another embodiment of the hood of the invention;

5 FIG. 5 is a view showing one type of arrangement for securing the panels of the hood of FIG. 1;

FIG. 6 is a sectional view along line VI—VI of FIG. 5;

FIG. 7 is a view showing another type of arrangement for securing the panels of the hood of FIG. 4; and

FIG. 8 is a view showing another type of arrangement for securing the panels of the hood of FIG. 4.

In FIGS. 1 and 2, an embodiment of the exhaust receiving apparatus or hood 11 of the invention is shown in operative position relative to a basic oxygen furnace converter 13. The hood 11 includes a reticular structural frame 15 and a plurality of refractory panels, designated generally as 17; the panels 17 being removably secured to the reticular structural frame 15.

In FIG. 3, the reticular structural frame 15 is comprised of tubular members 19, each member having a hollow head portion 21 and a stem portion 23, and resembling structural T's in cross-sectional shape. The T-members 19 are advantageously interconnected in such a manner that a cooling fluid, such as water, courses through head portions 21 of the reticular frame 15 to cool the frame. The hollow rectangular shaped tubular head portion 21 and the planar stem portion 23 are, preferably, integrally formed. However, the planar stem portion 23 may be welded to the hollow head portion 21, about where shown in FIG. 3. The planar stem portion 23 is provided with a plurality of spaced apart holes or apertures 25 which are used to secure the panels 17 to the frame 15.

Referring to FIGS. 1 and 3, the tubular Tee members 19 are connected together to form the reticular frame 15 of the hood 11 which generally has a rectangular cross-sectional shape.

The region of the hood 11 nearest the mouth of a basic oxygen converter 13 is an entrance region 27 for the substantial volume of gases emanating from the converter 13. The other end of the hood is an exit region 31 which is generally connected to other gas receiving apparatus (not shown) for the purpose of conducting the gases away from the furnace and treating them.

45 The refractory panels 17 are removably secured to the reticular frame 15. As illustrated in FIG. 3, each panel is comprised of a grid 33 of structural members, such as the marginal channel members 35 which encompass the periphery of the panel 17, and the intermediary I-beam members 37 which are disposed generally transversely of the panel grid and which are secured to the marginal members as by welding, or in any other suitable manner. Within the spaces of the grid 33, there is a suitable refractory material 39 which may be cast within the grid, or a suitable refractory in the form of bricks; such refractory materials being formed so that the panel has generally planar front and back surfaces. In the embodiment shown in FIG. 3, the front and back surfaces of the panel 17 are flush with the front and back surfaces of the grid members 35, 37. The hood of FIG. 1 comprises a frame 15 and a plurality of such panels 17. The panels 17 are, of course, so made that they fit in the various shaped openings of the reticular frame 15; that is, some panels are rectangular, some trapezoidal, and some may be triangular in other applications.

It is a feature of the invention that the panels 17 are readily and quickly removable and replaceable in the frame 15. Generally, the panels can be quickly and easily removed from the reticular frame to effect repairs, using suitable auxiliary equipment as required. Such repairs may be made between successive blowing cycles if con-

venient, or during a normal furnace repair and overhaul campaign.

The refractory material, preferably, is capable of withstanding the severe service conditions including: high ambient temperatures; abrasion by particulate matter in the exhaust gases; oxidation and reduction atmosphere produced within the hood during a complete blowing cycle; water sprays; and the like.

Referring to FIGS. 1 and 3, it will be noticed that the individual refractory panels 17 are secured in the reticular frame 15 in a novel manner. Each panel 17 rests upon the stem portion 23 of the adjacent lower tubular member 19, and the marginal channel portion 35 abuts the encompassing vertically disposed tubular head portions 21. The holes or apertures 25 in the stem portions 23 are so located that when a tapered panel-retaining pin 41, such as is shown in FIG. 3a, is inserted in each hole they bear against the outer surface of the panel and urge it into a fixed position within the reticular frame. Each tapered panel-retaining pin 41, is provided with a small hole 43 in its smaller end portion wherein a keeper pin 45, such as a conventional cotter pin or the like, may be inserted.

Thus, it is a simple matter to remove each panel by first removing the keeper pins 45, then removing the panel retaining taper pins 41, and lastly removing the panels themselves by means of suitable auxiliary handling equipment. To readily effect the removal of each panel, there may be provided suitable handling lugs or brackets (not shown) on the grid structure of the panel to which a crane hook, or other auxiliary lifting equipment, may be attached.

The foregoing has described an embodiment of the novel hood of this invention. The hot gases flowing from the basic oxygen furnace or converter 13 enter the hood 11 at 27 and pass through to auxiliary equipment where the gases are cooled and otherwise disposed of. As has been pointed out, the temperature of these gases are high, for example 3500° F. or higher; the discharge of gases may last from 22-25 minutes; and huge quantities of the gases pass through the hood. During the period of operation, water may, if desired, be flowed through the hollow head portion 21 of the frame members to cool the frame structure. However, since the panels 17 themselves are of refractory material which is highly resistant to heat, water cooling of the panels is unnecessary.

If after a considerable period of operation one of the panels 17 becomes cracked or defective, it is a simple matter to remove the keeper pins 45 from the taper pins 41, and then remove the panel 17. Another panel can then quickly be inserted in the space in the frame, the retaining pins 41 placed in position and the keeper pins 45 inserted in their proper place, locking the retainer pins in place. The hood is again ready for operation.

The ease with which a panel can be replaced in the present invention of course, is in contrast to the heretofore known methods for repairing other types of hoods where whole sections must be replaced. In some cases even the entire hood structure had to be replaced.

Since water cooling is required only in some embodiments of the present invention and not at all in some other embodiments, described hereinafter, it is possible with this invention to materially decrease the weight of the structure and thereby save, for example, in the pumping apparatus that is required to flow water through the usual water jacket type structure. To this end, FIG. 4 illustrates a portion of another embodiment of the hood 11 wherein a structural reticular frame 47 is comprised of transversely disposed H-type beams 49 which are connected to other marginal H-type beams 51 around the perimeter of the hood. A plurality of refractory panels 53 are removably secured in the spaces of the reticular frame 47 thereby forming the walls of the effluent gas conducting hood.

Each refractory panel 53 is substantially similar to the refractory panel 35, except that in the embodiment of

FIG. 1, a deeper marginal channel 55 is used around the periphery of the panel and an additional H-type beam 57 is transversely disposed within the panel at substantially the midpoint of its height. On the web portion of the horizontal H-type beam 49, there are a plurality, though only one is shown, of cam-lever clamps 59, which are pivotable in a conventional manner and which secure the refractory panel 53 in position to the reticular frame 47. When the cam-lever clamp 59 is in the position, as indicated by solid lines in FIG. 4, the refractory panel 53 is in the secured or locked-in position; and, when the cam-lever clamp 59 is in the position indicated by the dotted lines in FIG. 4, the refractory panel 53 is in the released position, and may be readily removed from the reticular frame 47.

FIGS. 5 and 6 illustrate another embodiment of the hood of the invention wherein a refractory panel 61 is provided with upwardly and downwardly extending hasps 63 which are fixed to, as by welding, a marginal channel member 65 (similar to the marginal channel 35) and which cooperate with outwardly extending staple members 67, that are fixed to a tubular T member 69. When such refractory panels 61 are inserted in the reticular frame formed of the tubular T's 69, the inner surface 25 of the panels 61 is substantially flush with the interior surface of the frame T members 69.

Each such refractory panel 61 may be removably secured to the reticular frame and maintained in place by means of a keeper pin or wedge-pin 71, such as is indicated in FIGS. 5 and 6.

While not so illustrated in the drawings, the refractory panels 53 may also be provided with suitable lifting lugs or brackets whereby each panel may be removed from and replaced in the reticular frame 69, in the manner heretofore described.

In FIG. 7, there is illustrated still another embodiment of the invention, wherein the exhaust hood is comprised of a refractory panel 73 and a structural reticular frame 75. The reticular structural frame 75 of this embodiment, however, is comprised of H-type structure members 77 which, as will be noticed, are not water-cooled as are the tubular frame members 15 and 69 of FIGS. 3 and 5. In the embodiment of FIG. 7, the structural reticular frame 75 is maintained in spaced apart relation to the heated refractory surfaces of the panels 73, and are therefore substantially air-insulated from the heat of the refractory panels.

Each panel 73, in the embodiment of FIG. 7, is comprised of a grid or frame structure 79 which includes marginal channel members 81 that are similar to the marginal channel members 35, and H-beam members (or I-beam members) 83 which are similar to, but substantially deeper than, the I-beam members 37 mentioned previously. The refractory material of the panel of FIG. 7 is preferably the same as the refractory material 39 of the panel of FIG. 3. It will be noticed from FIG. 7, however, that the thickness of the refractory panel 73 is only about one-half the depth of the H-beam structural member 83.

The structural reticular frame 75 is provided with a plurality (though only one is shown) of outwardly projecting staple-like members 85 which cooperate with suitably sized apertures 87 in the outwardly facing flange of the H-beam member 83. Each such staple-like member 85 is also provided with an aperture 89 wherein a keeper pin or wedge 91 may be inserted to secure and maintain the panels 73 in position in the reticular frame 75.

As shown in the embodiment of FIG. 7, the marginal channels 81 of adjacent refractory panels 73 abut along their respective web portions and, it is a simple matter to make an air-tight seal between the abutting channels, if necessary, by simply placing a suitable sealant there-between.

A feature of the hood of FIG. 7 is that the structural reticular frame 75 is air cooled by virtue of being spaced apart from the heated surfaces of the refractory panels 73. An additional feature of the hood of FIG. 7 is found in the smooth interior surface formed by the adjacent abutting refractory panels 73.

FIG. 8 illustrates a modification of the arrangement for securing the panels 73 of FIG. 7 to the frame 75; the modification consists in replacing the staple 85 and apertures 87, 89 of FIG. 7, by a wedge block 91 and a coacting keeper wedge 95.

The wedge block 91 is fixed, as by welding, to the horizontal web portion of the H-beam frame member 77, and in one face portion of the wedge block 91 there is a tapered groove 93 which is adapted to receive the keeper wedge 95 which has therein an elongated longitudinal slot 97. The wedge block 91 may also have in its bottom a slot 99 for the purpose of allowing water or other liquid, which may accumulate on the horizontal web of the H-beam member 77, to pass therethrough and not accumulate on one side of the wedge block. When the panels 73 have been placed in the reticular frame in their respective operative positions, the wedges 93 can then be inserted in the slots 97, and urged downward in the wedge block 91 to removably secure and maintain the panels 73 in the frame. Now, in order to remove and replace such panels, it is only necessary to insert a suitable tool in the longitudinal slots 97 and pry or urge the keeper wedges 95 upward and out of the tapered grooves 93. Thereafter, the panels 73 may readily be removed, using suitable auxiliary handling equipment; it being understood that the panels 73 may be provided with suitable lifting lugs or brackets mentioned hereinbefore.

Those skilled in the art will recognize that the refractory panels of the present invention can be made in such a manner that the optimum qualities of the refractory materials are fully used, and the panels perform with the highest efficiency. Moreover, the reticular frame structure is relatively light in weight, is simple to construct, and the use of the highly refractory materials in the panels results in an exhaust hood that is less expensive and more effective.

The panels of the present structure, also, can be readily and quickly repaired and maintained with a minimum of lost time and expense; there will also be a minimum of lost furnace time during regular maintenance campaigns. That such economies are effected in the hood of the present invention is due to the panels being readily and quickly removable and replaceable from the reticular frame.

The hood structure of the present invention, moreover, requires a minimum of water cooling. Only the frame structure in the embodiments of FIGS. 3 and 5 are water cooled; in the other embodiments no water cooling is required. That such a hood represents a material and significant saving in initial investment and operating expense should be evident to those skilled in the art.

Although the foregoing describes with a certain degree of particularity a preferred and other embodiments of the invention by way of an example, it is understood that the invention is not so limited, but is defined by what is hereinafter claimed.

I claim:

1. A hood for a metallurgical furnace comprising:
  - (a) a reticular frame disposed relative to said furnace including a plurality of spaced apart fluid conductive interconnected members;
  - (b) a plurality of panels of refractory material mounted in said reticular frame and forming the effluent conducting walls of said hood;
  - (c) means to circulate coolant in the fluid conductive members of said frame structure; and
  - (d) means to removably secure in operative positions said panels to said reticular frame.

2. A hood for a metallurgical furnace comprising:
  - (a) a reticular frame including a plurality of spaced apart fluidly intercommunicative tubular members wherein a cooling medium flows and maintains said frame cool;
  - (b) refractory panels mounted to said reticular frame forming the effluent conducting walls of said hood, said panels being comprised of grid supported refractory material; and
  - (c) means for removably securing said panels in operative relation to said reticular frame.
3. The invention set forth in claim 2 wherein:
  - (a) said fluid conductive tubular members are provided with means on which said panels are supported.
4. The invention set forth in claim 3 wherein:
  - (a) said panel supporting means has apertures therein; and
  - (b) means adapted for inserting in said apertures are provided whereby said means coacts with said frame and panel to removably secure said panel in operative position to said frame.
5. A hood for a metallurgical furnace comprising:
  - (a) a reticular frame including a plurality of spaced apart interconnected members;
  - (b) refractory panels comprised of a grid and refractory material connected thereto adapted for mounting to said frame and forming the effluent conducting walls of said hood;
  - (c) hasps mounted on each said panel;
  - (d) eyes mounted on said frame for cooperation with said hasps; and
  - (e) means for securing said cooperative hasps and eyes whereby each panel is removably secured to said frame.
6. The invention of claim 5 wherein:
  - (a) said eyes have apertures therein; and
  - (b) a wedge is insertable in said eye whereby said hasp and the panel connected thereto is urged into operative position relative to said frame to form the effluent conductive walls of said hood.
7. A hood for a metallurgical furnace comprising:
  - (a) a reticular frame including a plurality of spaced apart interconnected members;
  - (b) an eye fixed to said frame and projecting therefrom;
  - (c) refractory panels comprised of a grid and refractory material connected to said grid adapted for mounting to said frame and forming the effluent conducting walls of said hood, at least one said grid member of each panel having an aperture therein adapted to cooperate with an eye fixed to said frame; and
  - (d) means cooperating with the aperture in said eye to urge said panel into a removably secured relation to said frame.
8. The invention set forth in claim 7 wherein:
  - (a) said eye has therein an aperture; and
  - (b) a wedge is inserted in the aperture of said eye for removably securing said panels in operative position relative to said frame forming the effluent conductive walls of said hood.
9. The invention set forth in claim 7 wherein:
  - (a) said frame is spaced and maintained apart from the refractory panel surfaces whereby an air-insulating space is created between said frame and the refractory surfaces of said panels.
10. A hood for a metallurgical furnace comprising:
  - (a) a reticular frame including a plurality of spaced apart interconnected members;
  - (b) refractory panels comprised of a grid and refractory material connected thereto adapted for mounting to said frame and forming the effluent conducting walls of said hood;
  - (c) wedge blocks mounted to said frame and having in one surface a tapering groove;

- (d) means to position a portion of said panel between the grooved surface of said wedge blocks and said frame; and
  - (e) a wedge disposed in said tapered grooves cooperating with said wedge blocks and said panel to urge said panel against said frame whereby said panel is removably secured in said frame.
11. A hood for a metallurgical furnace comprising:
- (a) a reticular frame including a plurality of spaced apart interconnected members;
  - (b) refractory panels comprised of a grid and refractory material connected thereto adapted for mounting to said frame and forming the effluent conducting walls of said hood; and
  - (c) pivotal cam levers mounted to said frame;

- (d) means to position a portion of a panel between said cam lever and said frame whereby when said cam lever is actuated said panel is wedged against said frame and said panel is removably secured in said frame.
